HYGROMETRIC MEANS

Edward Frank Spanner, London, England

Application December 10, 1943, Serial No. 513,799
In Great Britain August 30, 1943

2 Claims. (Cl. 73—338)

1

This invention relates to hygrometric means and has for objects greater convenience, increased accuracy and more dependability than has been possible in the past with commercial and industrial contrivances.

The invention has reference to hygrometric means of that kind in which so-called wet and dry bulb thermometers are used to ascertain the depression of temperature caused by the evaporation of water in a current of the ambient air.

The invention contemplates means by which the flow of ambient air past a remotely disposed and inaccessible wet bulb can be controllably aspirated, thus enabling wet bulb temperature readings of unvarying accuracy to be obtained by inducing effective evaporation from the wet bulb whenever desired.

The invention also contemplates means by which a dry bulb temperature reading of reliable accuracy can be obtained from a thermometer having a remotely disposed and inaccessible wet bulb by positively preventing evaporation from said wet bulb on occasion.

The invention also contemplates means by which deleterious materials or substances are removed from the current of ambient air flowing past the wet bulb so as to prevent any alteration in the absorptive or evaporative character of the wet bulb clothing.

The invention also contemplates the determination of the dew point in closed compartments or storage chambers which may have metal walls exposed to varying temperature, such as the holds on board ship.

The invention also contemplates installations by which tests can be made and recorded every few hours so that adequate precautions can be taken to protect the cargo or goods stored in closed compartments.

Generically the invention provides hygrometric means comprising a single thermal responsive element, an absorbent clothing for said element, means for wetting said clothing with water, a chamber for said clothed element, sealing means for said chamber, means for aspirating the air to be tested past said sealing means and over said clothed element temporarily for short periods of time fully to depress the temperature of said element and means connected to said element for ascertaining the thermal condition of said element in stagnant air and in flowing air.

In the drawings:

Figure 1 is a schematic showing, partly in section, of one form of test apparatus;

Figure 2 is an exterior view of Figure 1;

2

Figure 3 is a diagram showing an installation as an example of how the invention may be applied;

Figure 4 is a view showing a fragment of a temperature graph chart obtained from the apparatus shown in Figure 1;

Figure 5 is a schematic showing, partly in section, of a modified form of test apparatus.

Figure 6 is a diagram somewhat similar to Figure 3 but in which only a single indicator is employed in conjunction with a multiple way switch.

Figure 7 is a diagram somewhat similar to Figure 6, but in which a multiple way valve is associated with the multiple way switch.

15 Figure 8 is a diagram of a three compartment installation operated automatically every three hours.

Referring to Figures 1 and 2, *a* is the casing containing the thermal responsive element of a thermometric device, such for example as an electrical resistance, *b* is a tube of textile or other absorbent material which encloses the operative end of the casing *a* and continues as a wick *b* that passes through the perforated guard *c* into the tank *d* that contains distilled water.

20 The casing *a* and enveloping tube *b* are sealed into a small closed chamber *e* having an exhaust pipe *f* and an inlet valve that may consist of a thin metal disc *g* having guide legs *h* and which normally, for example by the action of gravity, 25 covers the perforations *j* in the seating *k* that forms part of the bottom of a chamber *l* having a plug of non-hygroscopic dust collecting material *n* of known kind supported therein.

30 In the installation shown in Figure 3 there are three compartments *X*, *Y* and *Z*, each of which is fitted with a test apparatus of the kind shown in Figures 1 and 2, the thermal responsive elements in the casings *a* being connected to the 35 thermometric indicators, shown by way of example as recorders *o*, located at testing stations *x*, *y* and *z* disposed remotely in convenient positions whilst the exhaust pipes *f* are connected to the 40 suction pipe line *p* through control cocks *x*¹, *y*¹ and *z*¹ located at the stations *x*, *y* and *z* respectively.

45 In Figure 3 the pipe line *p* is shown as connected to a direct acting aspirator *q* by way of example only, it being obvious that any kind of air suction means providing the requisite head, may be used.

50 Recorders such as *o* usually are provided with means by which the graphic record can be interrupted, such as pen-lifting contrivances, and in the present instance it is assumed that when 55 recorders are used, normally the pens *r* of all the

recorders o are raised from off the charts on the time driven drums s and the cocks x^1 , y^1 and z^1 are closed.

The initial step in making a test is to lower the pen r on to the drum s at a station, say x for example, to trace the short line u parallel with the horizontal lines of the chart as shown in Figure 4, thus indicating the dry bulb temperature of the ambient atmosphere in the compartment X ; the cock x^1 is then opened thus drawing air from the compartment X through the filter material n , past the valve disc g and through the chamber e over the wet tube b enveloping the casing a .

The evaporation of the water saturating the tube b , by the abstraction of heat in known manner, depresses the temperature of the casing a temporarily, thus causing the pen r to trace the downwardly tending oblique line v on the chart as the drum s is rotated by the clockwork relatively to time and this obliquity continues until the temperature due to the evaporation ceases to change, thereafter the line w parallel with the horizontal lines of the chart is traced and the test is finished.

To economise in time and to enable a number of readings in close time relation to be taken by one person making the test, as soon as the cock x^1 is opened, the inspector may go to the second station, say y , drop the pen r on to the chart on the drum of the recorder o at that station to obtain a test line u parallel with the datum line, open the cock y^1 , then go to the third station z , drop the pen r on to the chart on the drum s of the recorder o at that station to obtain a test line u parallel with the datum line, open the cock z^1 then go to the next station and so on, returning to station x in from about five to ten minutes to raise the pen r , and close the cock x^1 , visiting the stations y , z and so on in proper order to obtain a set of charts similar to that shown in Figure 4, one for each of the compartments X , Y and Z .

On the chart shown in Figure 4, u indicates a value precisely similar to the reading of a dry bulb thermometer and w indicates a value precisely similar to the reading of a wet bulb thermometer in the conditions under test, thus enabling the relative humidity and dew point of the ambient air to be ascertained by referring these wet and dry bulb readings to a standard dew point chart.

It is to be observed that although only a single thermometric device is used to determine both the dry bulb and wet bulb readings, the accuracy of the readings is reliable because the rate of evaporation can be regulated from zero for the dry bulb reading to a predetermined and effective rate of evaporation by creating and maintaining a head of negative pressure in the pipe line p whilst taking a wet bulb reading.

A particular advantage that accrues from the apparatus shown in Figures 1 and 2 is that it can be so proportioned that it can be stowed or placed in a position that is accessible only at long intervals of time, say every two, three or more months.

Continued service depends entirely on the supply of water and it is one feature of the invention that in the apparatus shown in Figures 1 and 2, evaporation and hence loss of water cannot take place except during test, owing to the valve disc g , and the cocks x^1 , y^1 and z^1 which positively shut off all access of air. Further, the quantity of water evaporated during each test

is extremely small since the means provided ensure that this is reduced to the minimum necessary to depress the temperature fully and in a reliable way.

Owing to the presence of the filter material n the aspirated air is freed of solid particles before it contacts with the tube b and owing to the use of distilled water there is substantially no deposition of foreign substance on the absorbent material clothing the bulb or on the surface of the bulb so that the effectiveness of the evaporation is always maintained at a high standard; also, it is to be noted that although the quantity of water evaporated during each test will vary with the dew point of the ambient air, it is quite easy to assume a worst possible condition and to calculate the volume of water necessary to make a test say, every four hours for sixty days, that is three hundred and sixty tests and add a safety margin of a generous kind to ensure reliable service.

All the results can be obtained on a single chart by using a multiple way switch for connecting the thermal responsive element of any test apparatus to a single recorder o , providing a multiple way valve for connecting the exhaust pipe f of that test apparatus to the exhausting pump q and operating the switch and valve by hand at proper time intervals to obtain readings from the thermal responsive elements in sequence, the switch and valve in some cases being mechanically coupled to eliminate all risk of irregular manipulation.

When it is desired to maintain continued observation of the conditions in the several compartments or enclosures automatically, the switch and the valve may be linked together mechanically and operated by power means at stated intervals of time sufficiently separated (say by more than two hours) to enable the thermal responsive elements to acquire the temperature of the ambient atmosphere in each compartment.

The initial step in every test is to observe if the indicator remains steady for about, say, thirty seconds or to obtain the tracing of a line similar to the line u of Figure 4 for, say, about one half minute and the final step is to observe if the indicator remains steady for about, say, sixty seconds or to obtain the tracing of a line similar to the line w of Figure 4 for, say, about one minute and the aspiration must be maintained until the pen r traces a line such as w parallel to the datum line for at least one minute, thus showing that the wet bulb temperature has fallen to a steady level proper to the humidity of the ambient air, that is, the air being drawn past the wet bulb to cause evaporation.

In the arrangement shown in Figure 5 the tube b , of textile or other absorbent material enveloping the casing a of the thermal responsive element, is maintained dry normally and only wetted during test.

As in the previously described example, the casing A with its enveloping tube b is sealed into a closed chamber e having an exhaust pipe f , dry bulb temperatures being taken before starting up the exhausting pump q to obtain the recorded line u on the chart.

To obtain a "wet bulb" effect, the tube b is saturated temporarily with a small quantity of water which may be delivered to it from a water supply pipe t through the measuring valve t^1 included in the water supply, said valve being operated after the "dry bulb" reading has been taken.

Aspirated air is then drawn through the louvred wall *m* into the chamber *l* filled with dust collecting material *n* past the perforations *j* into the chamber *e* through which it flows over the tube *b* to the pipe *f*, and thence to the pipe line *p*. The flow of ambient air over the wet bulb causes effective evaporation and a fall of temperature similar to that indicated by the line *v* in Figure 4, the terminal line *w* parallel with the datum line being dependent upon the dew point of the ambient air.

In Figure 6 the exhaust pipes *f* are so disposed that the cocks *x*¹, *y*¹ and *z*¹ are in juxtaposition and the electrical conductors from the casings *a* are led to the multiple way switch *A* and connected to the contacts 1, 2, 3 and 11, 12, 13 so that when the mechanically connected pivoted contact arms 4 and 5 co-operate with the contacts 1 and 11 respectively, the indicator *o*¹ is electrically connected to the temperature responsive resistance in the casing *a* in the compartment *X* and the cock *x*¹ has to be opened, when the contact arms 4 and 5 co-operate with the contacts 2 and 12 respectively, the indicator *o*¹ is electrically connected to the temperature responsive resistance in the casing *a* in the compartment *Y* and the cock *y*¹ has to be opened and so on.

In Figure 7 the exhaust pipes *f* from the casings *a* in the compartments *X*, *Y* and *Z* are connected to the branches *x*², *y*² and *z*² respectively, of the body *f*¹ containing a revoluble plug *f*² having a portway *f*³ so that the pipe line *p* from the air suction means *q* can be connected to any of the chambers *e* by moving the handle *F* appropriately. To obtain indications or recordings of the thermal conditions in the compartments *X*, *Y*, *Z*, the contact arms 4 and 5 of the multiple way switch *A* are extended backwardly and connected to the handle *F* by the connecting rod 20 so that when the aspirator *q* is connected to the chamber *e* in the compartment *X* the indicator *o*¹ or the recorder *o* is electrically connected to the temperature responsive resistance in casing *a* located in the same chamber and similarly for the chambers *e* in the compartments *Y* or *Z*, selection between the recorder *o* and indicator *o*¹ being effected by the two way switch *B*.

In Figure 8 the branches *x*², *y*² and *z*² as well as the contacts 1, 2, 3 and 11, 12, 13 are equiangularly spaced, the spindles of the plug *f*², the contact arm 4 and the contact arm 5 having worm wheels 21, 22 and 23 respectively mounted thereon. These worm wheels co-operate with worms 24 mounted on the spindle 20^a rotated by the electro-motor 25. The electro-motor 25 operates intermittently, say for example, every hour, under the control of the clock switch 26 having a contact arm 27, rotated by clockwork (not shown) once in every twelve hours, and contacts 28, of which twelve are provided with the electro-motor 25 is to be operated every hour. The contact arm 27 and contacts 28 are connected in electrical circuit with the local battery 29 and relay 30 to close the power contacts 31 and complete the circuit of the mains through the electro-motor 25 for a sufficient period of time to move the portway *f*³ and the contact arms 4 and 5 accurately and positively to the next succeeding operative position.

It is to be understood that the multiple way valve, the multiple way switches and the clock controlled relay power switch shown are meant to represent only ordinary known devices ca-

pable of operating to produce the required result and may be replaced by any other known contrivances for the same purpose.

The basic feature of the invention, namely the repeated obtention of reliable wet and dry bulb temperature readings, from a wet bulb thermometer inaccessibly located, at comparatively short intervals of time, say, every few hours over a long period, say several months affords data as to the dew point of the ambient air in proximity to the thermometer which are of particular value in enabling the ventilating conditions of the stored goods or substances to be modified so as to preserve said goods or substances from damage by heat and moisture.

This invention is especially applicable to conditions on board ship where condensation in a hold causes wetting of the cargo and irretrievable damage to grain (by providing conditions favourable to germination or mildew or decay) to metal (by rust and corrosion) to ammunition (by decomposition) and indeed to most stowage.

To avoid condensation on the ship's side, deck and bulkheads bounding a hold, it is necessary that the dew point of the air in the hold should be kept below the atmospheric temperature outside of the holds and to avoid condensation on cargo in the holds, it is necessary that the dew point of the air in the hold should be kept below the lowest temperature to which the cargo has been exposed until the cargo has warmed up.

Knowledge of the dew point in a hold is an essential preliminary to obtaining control of the dew point, and this invention is concerned with methods of accurately securing this knowledge.

Certain knowledge, frequently, of the dew point in the holds is therefore of supreme importance and this knowledge can be obtained from published charts when the wet and dry bulb temperatures have been ascertained by the means described hereinbefore.

The present invention is sharply distinguished from known arrangements for a similar purpose in that the condition of the air in the closed space is measured in the space itself, although the value of measurement is recorded at a considerable distance away, thus avoiding the inaccuracies due to the changes that arise in known installations when air is tested after having been aspirated through long pipes, the temperature of which varies at different parts, thus modifying the moisture content and temperature of the sample sufficiently to render it comparatively valueless for testing purposes.

55 I claim:

1. Hygrometric means comprising a single thermal responsive element, an absorbent clothing for said element, means for wetting said clothing with water, a chamber for said clothed element, an air inlet to said chamber, means for aspirating the air to be tested through said chamber and over said clothed element temporarily for short periods of time fully to depress the temperature of said element, a controlling valve for said inlet closed by gravity when aspiration ceases and means connected to said element for ascertaining the thermal condition of said element in stagnant and in flowing air.

2. Hygrometric means comprising a single electrical resistance thermometric element, a remotely located recorder for said thermometric element, an absorbent clothing for said thermometric element, means for wetting said clothing with water, a chamber for said clothed element, an air inlet to said chamber, remotely located

means for aspirating the air to be tested through said chamber and over said clothed element temporarily for short periods of time fully to depress the temperature of said element and a controlling valve for said inlet closed by gravity when aspiration ceases.

EDWARD FRANK SPANNER.
